RELAY

Henri Moreau, Paris, France

Application January 18, 1933, Serial No. 652,400
In France January 26, 1932

2 Claims. (Cl. 175—320)

Relays responsive to weak currents (such for instance as contact galvanometers) do not allow the use of powerful returning springs or other powerful resilient returning members.

5 The condition of sensitiveness requires, in fact, that the movable unit should be able to move under the action of a very reduced amount of energy. The returning spring must therefore be so much the more weaker as the required sensitiveness is greater.

10 On the other hand, the necessity of an electric contact as satisfactory as possible leads to giving the contacts a very small common section, in order that the unitary contact pressure should not be 15 too reduced. It results therefrom that the zone of contact is practically punctiform.

15 In these conditions, it sometimes happens that the contacts no longer separate, even when the circuit of the relay is open, as the returning spring is sometimes too weak for overcoming the ad- 20 herence of punctiform contacts.

The main object of the invention is to avoid this inconvenience and to render the operation of sensitive relays of the type indicated as safe and certain as that of ordinary relays.

25 The accompanying drawings illustrate, by way of example only, some forms of carrying the invention into practice.

Fig. 1 is a diagram relating to a first form of construction.

30 Fig. 2 is a diagram in which the energization of the relays takes place from currents circulating between the variable potential apices of a Wheatstone bridge.

35 Fig. 3 is a diagram of an installation for the control of temperatures.

Fig. 4 is a diagram of constructional modification.

Two sources of direct current shown at 1 and 2 40 in the form of rectifiers fed by a source of alternating current 1^a, are arranged in series in a circuit comprising two resistances 3 and 4; the whole is so adjusted that, normally, no current passes between the points 5 and 6 between which the winding 7 of a sensitive relay is arranged. In 45 other words, the rectifiers 1 and 2 form with the resistances 3 and 4 a closed circuit wherein a constant current circulates permanently; the resistances 3 and 4 are selected so that the points 5 and 6 of the said closed circuit are of the same 50 potential under normal circumstances. However, for instance, the resistance 4 is sensitive to the variations of temperature; it is therefore only at a predetermined temperature, for instance, 20 degrees centigrade, that the points 5 and 6 are of the same potential. The relay controls the clos-

ing of the circuit of apparatus such as a time switch device 8. A resistance 9 is arranged in the supply circuit of the rectifier 2, for the purpose hereinafter described.

If the temperature decreases, the resistance 4 5 also decreases. Consequently, the potential at the point 6 becomes lower than that at the point 5 and a current, first of low intensity, passes through the sensitive relay 7, the movable unit 7^a of which closes a contact at 7^b, and a current 10 flows in the circuit of 8. But the said circuit is in shunt with the terminals of the resistance 9. Consequently the difference of potential at the terminals of the primary of the transformer, which feeds the rectifier 2, increases. The difference of potential at the terminals of the secondary therefore also increases so that the potential at the point 5 increases, this determining a rapid increase of the current in 7 and the positive closing of the contact.

20 The time switch 8 controls, the energization of an electromagnet 10, and thereby, the inversion of a rocking mercury contact having a double tube and adjusted in such a manner that the tube 11 first causes the opening of the circuit of the time switch 8, and thereafter the circuit of the relay 7 25 is opened by the tube 12.

25 The time-switch device is of any known type comprising a relay which when it is energized, acts upon a movable armature which closes a contact, and is then released after a predetermined time by a clockwork movement. The relay 10 remains energized as long as the clockwork mechanism has not released the armature for breaking the contact of the energizing circuit of the said relay.

30 In the diagram of Fig. 2, a Wheatstone bridge is provided with groups of resistances 13, 14, 15, and 16; a relay 19 is arranged between the points 17 and 18 which are normally at the same potential during normal conditions, no current passes through this relay.

35 The armature of the relay 19 is arranged for closing the circuit of an electromagnet 23 when the said relay 19 is energized and this circuit electromagnet 23 is shunted at 21 and 22 on the resistances 13 and 14. The electromagnet 23 is 40 similar to the electromagnet 10 of the preceding example and the resistance 15, for instance, is similar to the resistance 4, that is to say it is sensitive to the variations of temperature. If the temperature decreases, the resistance 15 de- 45 creases. The potential at the point 18 increases and a current circulates from 18 to 17 while exciting the relay 19 which attracts its armature 20, thus closing the circuit of the electromagnet 23. It is obvious that as the closing of the contact 50 55

20 causes the passage of a current in the shunted circuit of 23, this determines a greater unbalancing of the Wheatstone bridge and an increase of the current passing through the relay 19; the 5 closing of the contact is therefore accelerated.

The value of the accelerating effect can be controlled. In fact, a suitable ratio can be established between the distances 21-17 and 17-22, and the direction of the current in the 10 shunted circuit at the same time as its strength can thus be controlled.

The contacts 7^a (Fig. 1) and 20 (Fig. 2) are resilient so as to bend when the excitation of the relays 7 (Fig. 1) and 19 (Fig. 2) is increased. 15 When these relays are de-energized, the resilient contacts 7 and 20 relax suddenly, thereby ensuring a perfect separation of the said contacts.

In the description of Fig. 3, the application of the invention to the control of the temperature 20 of a hot source is considered.

It is assumed that the temperature of the latter is controlled by two relays, which are not shown, but the circuits of which are indicated at 24 and at 25, respectively.

25 This temperature is applied, for instance, to one of the variable resistances of a Wheatstone bridge supplied at points 26 with current by a source of current 27. The adjustment is such that, at the temperature to be maintained, there 30 is no difference of potential between the apices 28 and 28^a of the Wheatstone bridge. The variation of this difference of potential, when it appears, takes place in the same direction as the temperature rise or fall.

35 A movable member is constituted by a rod 29, pivoted at 30 and carrying a soft iron armature 31 which can be pulled by either of the two electromagnets 32 and 33. The rod 29 carries mercury contacts or their equivalents 34, 35, 36, the 40 function of which will be explained later on.

The sensitive relay has an armature 37 provided with a contact piece 38 which can come in engagement with a fixed terminal 39, and two windings 40 and 41, the first energized from currents generated in the Wheatstone bridge 26, the 45 second energized by an independent source of current 42.

The relay 40-41-37 is made after the manner of a galvanometer, that is to say the armature 37 is displaced in one or the other direction according to the direction of the exciting current.

The operation is as follows:

The movable member 29 is in the position illustrated in the drawings and closes the circuit 55 24. If the temperature rises and exceeds the value to be maintained, a current is generated between the apices 28^a and 28 of the bridge 26 through the following circuit: apex 28^a, terminal 43 of the switch 36, mercury, terminal 21, wire 60 45, wire 45^a, winding 40 of the sensitive relay wire 46, wire 47, terminal 48 of the switch 35, mercury, terminal 49, and apex 28 of the bridge 26. The direction of this current is such that the armature 37 of the sensitive relay moves its 65 contact piece 38 in contact with the terminal 39 for closing a circuit as follows: one of the poles of the source of current 42, wire 50, electromagnet 33, wire 51, terminal 52 of the switch 34, mercury, terminal 53, wire 54, contact 39-38, armature 37, winding 41, to the other pole of the 70 source of current 42.

The energization of the winding 41 ensures the engagement of the contact 39-38, with resilient distortion of the armature 37, and the electromagnet 33 being energized, draws the movable

member 29 in a position symmetrical to that it occupies in the drawings. During the displacement of the movable member 29, the contact; terminal 53, mercury, terminal 52, is broken at the switch 34 and the contact 21—mercury 5 43—is also broken so that at the windings 40 and 41 are deenergized, and the resilient reaction of the index 41 suddenly breaks the contact 39-38.

When the movable member has reached the 10 position symmetrical to that it occupies in the drawings, the circuit 24 is broken, and the circuit 25 is closed. The temperature of the hot source begins to lower and becomes nearer the adjusting value. The armature 37 remains well away from 15 the contact piece 39, because a current of reverse direction to the preceding one passes through the winding 40, through the following circuit: apex 28^a of the bridge, terminal 43 of the switch 36, mercury, terminal 55, wire 46, winding 40, 20 wire 45^a, wire 56, terminal 57 of the switch 35, mercury, terminal 49, and apex 28 of the bridge.

The conditions remain the same as long as the temperature at the hot source does not fall below its adjusting value.

But when this temperature decreases below the adjusting value, a difference of potential appears between the apices 28 and 28^a of the bridge 26, this difference of potential is evidently inverse to that of the preceding case and produces 30 a current through the following circuit: apex 28, terminal 49 of the switch 35, mercury, terminal 57, wire 56, wire 45^a, winding 40, wire 46, terminal 55 of the switch 36, mercury, terminal 43, and apex 28^a of the bridge. The direction of 35 this current in the winding 40 is, as can be seen, that causing the armature 37 to move towards the contact piece 39. As soon as the contact 39-38 takes place, a circuit is closed as follows: one of the poles of the source of current 42, wire 40 58, electromagnet 32, terminal 59 of the switch 34, mercury, terminal 53, wire 54, contact 38-39, winding 41, to the other pole of the source of current 42. The winding 41 is energized by a current of the same direction as that considered 45 for the position of the movable member 29, position indicated in the drawing. The electromagnet 32 being energized, it restores the movable member 29 in the same position and everything is as it was initially.

Instead of a Wheatstone bridge, it is possible, in certain cases, to use photo-generating cells mounted as shown in Fig. 4, that is to say substantially as the sources of current 1 and 2 of Fig. 1. The cell 60 is lighted by a source of light of constant intensity, and the cell 61 is lighted with variable intensity according to the production of phenomena the effects of which are to be controlled (heat, temperature, light, etc.). For a definite illumination of the cell 61, no current 60 circulates between the points 28' and 28^a which are connected to the points 28 and 28^a of Fig. 3, when the bridge 26 has been done away with. For a smaller or greater illumination, a current in one direction or the other circulates between the 65 points 28 and 28^a, from which current the effects already described can be obtained, with an installation such as that of Fig. 3, the sun can be caused to intervene in the automatic regulation of central heating plants.

The commercial application of the galvanometric contacts, improved as just stated, to the control of relays for effecting various functions allows to obtain accuracy unknown up to this day. Thus, the invention applied to the thermal 70

regulation of furnaces, ovens etc. allows the control plant to be responsive to differences of temperature inferior to one-tenth of a degree. In fact, it is obvious that the invention allows to derive profit from the entire sensitiveness of galvanometers the index of which is responsive to currents of the order of 50 thousandths of a milliampere. These currents are those which occur in Wheatstone bridges having resistances variable with the temperature and when the latter varies to the extent of one-tenth of a degree, or with photogenerating cells, thermo-electric couples, etc.

What I claim as my invention and desire to secure by Letters Patent is:

1. In a relay, a winding, a movable armature adapted to be displaced when the relay is energized, a fixed contact, a movable contact, means for operatively associating the movable contact with the armature and for pressing said movable contact against the fixed contact when the relay is energized, a Wheatstone bridge, a variable re-

sistance placed in one of the arms of the bridge, a source of electric current connected to two opposite apices of the bridge, the winding of the relay being connected to the two other apices, a service circuit comprising the contacts of the relay and shunting a part of two adjacent arms of the bridge. 5

2. In a relay, a winding, a movable armature adapted to be displaced when the relay is energized, a fixed contact, a resiliently distortable 10 movable contact, means for operatively associating the movable contact with the armature and for pressing the movable contact against the fixed contact when the relay is energized, a Wheatstone bridge, a variable resistance placed 15 in one of the arms of the bridge, a source of electric current connected to two opposite apices of the bridge, the winding of the relay being connected to the two apices, a service circuit comprising the contacts of the relay and shunting a 20 part of two adjacent arms of the bridge.

HENRI MOREAU.
